UNITED STATES PATENT OFFICE.

NORTON A. NEWDICK, OF COLUMBUS, OHIO, ASSIGNOR TO THE COLODER COMPANY, OF COLUMBUS, OHIO, A CORPORATION OF DELAWARE.

SECTIONAL TRACKWAY.

Application filed February 23, 1922. Serial No. 538,700.

To all whom it may concern:

Be it known that I, NORTON A. NEWDICK, a citizen of the United States, residing in Columbus, in the county of Franklin and 5 State of Ohio, have invented certain new and useful Improvements in Sectional Trackways, of which the following is a specification.

This invention relates to an improved, 10 readily laid sectional track-way, and has for its primary object the provision of a track-way consisting of a plurality of similarly formed or duplicate sections which have their adjoining ends removably yet 15 securely connected together to retain the sections of the track-way in longitudinal alignment, without employing the services of the ordinary fish plates and the usual securing devices associated therewith, and for 20 the purpose of enabling the track-way to be quickly laid, irrespective of underlying foundation or ballast conditions.

Another object of the invention resides 25 in the provision of a sectional track-way wherein each of the respective meeting ends of the rail sections of the trackway are united by means of an improved hinge connection, and wherein the said connection is strengthened and made possible by means 30 of a shelf or chair plate rigidly projecting from the end of one of said sections and arranged to underlie the adjoining ends of the other of said sections, the arrangement being such that the passage of rolling stock 35 over the track-way will result in imparting the weight thereof substantially to the chair plates at the meeting ends of the rail sections, relieving the hinge connection from strain and thereby providing a track-way 40 generally of all requisite strength for carrying out its intended objects.

A further object of the invention rests in the provision of a sectional track-way adapted 45 for use especially in underground mines, for providing a secure track-way over which the rolling stock of such mines, for example loading machines, or mine locomotives, may readily pass, the specific construction of the track-way being such that the track may be 50 particularly used in connection with loading machines, since the features of the track-way are such as to admit of the convenient laying of the track-way as the loading machine progresses toward the working face

of a mine, and also admit of sufficient tractive surface between the wheels of the loading machine and the tread surfaces of the rails to permit the loading machine, by its own power, to force its way into the materials to be loaded. 55

With these and other objects in view, that will appear as the description progresses, the invention consists in the novel features of construction, combinations of elements and arrangement of parts, hereinafter fully 60 described and pointed out in the appended claims. 65

In the accompanying drawing, forming a part of this specification:

Figure 1, is a top plan view of the improved sectional track-way comprising the present invention. 70

Figure 2, is a side elevation of the meeting ends of a pair of rail sections of the track-way and disclosing the hinge connections between said ends, and 75

Figure 3, is a vertical transverse sectional view taken on the plane indicated by the line 3—3 of Figure 1. 80

Referring more particularly to the details of the invention, and to the specific form of the latter, disclosed in the accompanying drawing, I provide the sectional track-way 1, which is formed, in this instance, to consist of a plurality of substantially duplicate sections 2. These sections are of any suitable length, and each of the said sections is formed to include a relatively broad or wide tread surface or web 3, arranged for engagement with the tread surfaces of the wheels of rolling stock adapted to pass over the track-way. To render the sections light, from a standpoint of weight, and yet to provide all due requisite strength for practical purposes, together with economy in manufacture, the tread surface or web 3 of each section terminates on the inner side thereof in a downwardly directed substantially vertical wall 4, which in turn terminates in an inwardly directed substantially horizontally situated base flange 5, and the inner edge of the flange 5 is formed integral with an upstanding longitudinally extending rib 6. It will be observed that by this construction, the wall 4, the base flange 5 and the rib 6 all serve to define in each section the longitudinally extending channel or groove 7, adapted for the reception of 85 90 95 100 105

the rail flange of a truck wheel, whereby during the passage of rolling stock over the track-way the latter, by reason of its flexibly connected sections will serve to automatically provide its own wheel gage. This construction is of primary importance in connection with emergency tracks.

To flexibly connect the meeting ends of said sections, I employ a hinge connection, designated generally by the numeral 8. This hinge connection is substantially the same as that discussed in the prior patent issued jointly to myself and W. E. Moody, Number 1,357,584 and patented November 2, 1920. Therefore, I do not claim this hinge connection, *per se*, but merely in combination with other features above described and hereinafter specifically set forth, of the track-way comprising the present invention. Each hinge connection consists of a pair of leaves 9 and 10, which in this instance are separately formed with the sections of the track-way but are permanently or rigidly secured thereto by means of fastening elements, for example, the rivets 11. It is manifestly possible to integrally form the leaves 9 and 10 with the meeting ends of said sections if this construction is desired. However, it has been found advisable from a practical standpoint, to separately form said leaves to admit of economic repair of the track-way in the event that one of said leaves becomes fractured. It will be observed, by reference to Figure 1, that the leaves 9 are located at one end of each of the sections of the track-way, and the leaves 10 at the other ends of said sections, as regards the leaves 9, and that the said hinge connections are disposed on the outer sides of said sections immediately adjacent to the respective meeting ends thereof. The leaves 10 each include a vertical wall 12, which is adapted to be arranged in engagement with the vertical outer walls 13 of the rail sections 2, and immediately above the outwardly turned base flanges 14 of said rail sections, which flanges 14 are disposed substantially in the same horizontal plane as the flanges 5. The rivets 11 are adapted to pass through the vertical walls 12 of the leaves 10 and also through the walls 13 of the rail sections. Each of the said leaves 10 is also formed with an outwardly directed horizontally extending shelf 15, which is provided with a depressed outer end 16, which forms the pocket 17, in each of the leaves 10 contiguous to the end of the rail section upon which the leaf 10 is mounted. This depressed outer end 16 is formed with a relatively elongated slot 18, adapted for the reception of the shank 19 of a locking stud 20, rigidly formed in connection with each of the leaves 9. The leaves 9 are similarly formed in a general way as the leaves 10 and include vertical walls 21, arranged for engagement with

the rail walls 13, and preferably riveted thereto as at 11. Also, the said leaves 10 have their vertical walls 21 terminated along the upper edges thereof in outwardly directed horizontally extending ears 22, upon which are formed the depending locking studs 20. It will be observed that each of these studs terminates at its lower end in an outturned laterally extending foot 23, which is proportioned so that when the leaves 9 are properly relatively positioned with respect to the leaves 10, the foot 23 of each stud will be capable of vertically entering the slot 18. It will be apparent by the virtue of this construction that to connect a rail section with a previously laid section, the section to be positioned is located angularly and horizontally to the fixed section, the angular relations between said sections being such as to admit of the passage of the foot 23 through the slot 18 until the under surface of the ear 22 engages with the upper surface of the depressed outer end 16 of the shelf 15. When this engagement occurs the foot 23 will be located beneath the under surface of the end 16, whereby upon oscillating the section to be laid horizontally and inwardly with respect to the track-way, the foot 23 will be forced to a position out of registration with the slot 18, thereby locking the sections together, and in substantially longitudinal alignment. If desired the sections may each be connected by bridles, but the use of such transverse ties is not necessary in the majority of instances, because of the previously described channel or groove 7, in each rail section which enables the track to be automatically gaged by the travel of truck wheels thereover.

I provide each rail section contiguous to the end thereof carrying the hinge leaf 10, with a rigidly secured underlying chair plate 24. This plate, as shown in Figure 1, is permanently secured or formed with certain of the ends of section 2 and so proportioned that the said chair will project beneath and support the end of an aligning rail section, the said plate being secured to said sections adjacent to the leaves 10 and arranged to underlie the ends of the sections carrying the leaves 9. By the provision of these plates it will be observed that I am enabled to employ the flexible hinge connection 8 and preclude undue breakage thereof. Thus, the chair plates 24 are so disposed as to underlie and bridge the gap formed between the joints of the longitudinal rail sections at the meeting ends of the latter, and therefore during the passage of rolling stock over the track-way, the weight of said rolling stock will be to a very considerable extent directly imparted to the chair plates, instead of being transmitted to the hinge connections, as is the case in the patent previously referred to. Thus, in the event of

an insecure foundation for the track-way, which condition is constantly encountered in mine work particularly, the inclusion of the chair plates 24 will serve to strengthen the 5 track-way at the meeting ends of the rail sections thereof, maintaining said sections substantially in the same horizontal plane, and preventing undue relative vertical movement therebetween. The hinge connections are thus enabled to possess a relatively extended life and will not break or fracture as they will do if unprotected when weight of any considerable extent is imparted thereto. It will thus be seen that the 10 present invention provides a track-way which especially is capable of being quickly laid, does not involve the use of fish plates, bolts, nuts and other similar fastening devices employed in track-way construction of 15 ordinary form. This track-way has been designed with a specific view in sight, that of enabling mining machinery to be readily advanced toward the working face of an underground mine. To secure efficient results from the use of such machinery and 20 to maintain the same constantly in operation, in the majority of instances it is necessary that a track-way be provided to enable the machine to follow the face of a 25 mine as the latter is worked out. Furthermore, the track must be capable of being quickly laid under adverse conditions, such for example, as a bad floor covered with water, ore or coal particles. Moreover, loading machines especially are adapted to be 30 forced into the materials to be loaded under their own power and therefore to secure this action it is necessary that the rails shall possess broad treads to permit of sanding 35 thereof, or, generally stated, to provide the necessary tractive grip between the wheels of the loading machine and the rails of the 40 track-way, to permit of the forcing of the machine into and under the coal or other 45 material to be loaded. The present invention contains these essential features and not only does it provide a mechanically improved track-way for special machinery but it is also an improvement in track-ways generally because of the saving effected in the 50 employment of labor in laying or positioning the same.

What is claimed is:

1. In a sectional track-way, a pair of rails, 55 a shelf having a slot formed therein projecting horizontally and outwardly from the end and the outer side of one of said rails, a shelf similarly projecting from the adjoining end of the other of said rails, a stud 60 carried by the last named shelf and arranged to be located in the slot of said first named shelf when said rails are in longitudinally aligned connected relationship, and a chair plate projecting from the end of said 65 rail carrying the slotted shelf and arranged

to extend under the rail carrying the other shelf to strengthen the joint formed between said rails.

2. In a sectional track-way, a pair of rail sections, separable hinges secured to the respective meeting ends of said sections, and a shelf rigidly formed with the end of one of said sections and projecting loosely beneath the other of said sections, at a position contiguous to said hinge members. 75

3. In a track-way, a rail section comprising a substantially hollow metallic body including a relatively broad horizontally extending tread surface, said tread surface terminating at the longitudinal edges thereof in downwardly extending transversely spaced sides, base flanges extending outwardly from the lower edges of said sides and integrally formed therewith, and an up-standing rib formed with the inner of said base flanges and serving to define a vertical receiving channel in said section. 80

4. A railway track rail shaped to double channel form longitudinally to provide an approximately plane wheel tread surface 90 and a wheel flange channel on one side and a plane supporting surface on the opposite side, and coupling elements extending from a corresponding side at opposite ends of the rail for separably joining the rail treads to 95 the adjacent rails.

5. A railway track rail shaped to double channel form longitudinally to provide an approximately plane wheel tread surface and a wheel flange channel on one side and 100 a plane supporting surface on the opposite side, coupling elements extending from a corresponding side at opposite ends of the rail for separably joining the rail treads to the adjacent rails, and a chair plate extending from one longitudinal end of the rail and at the base of the rail to provide a support for the end of the adjoining rail. 105

6. A railway rail for a portable track shaped to double channel form longitudinally to provide a wheel tread surface and wheel flange channel on one side of the rail, and a plane supporting surface on the opposite side, coupling elements projecting from the opposite longitudinal ends of the rail adapted to be engaged with a second rail when the latter is in an angular position 110 and interlockingly joined when the sections are in linear position. 115

7. A railway track rail shaped to double channel form longitudinally to provide an approximately plane wheel tread surface and a wheel flange channel on one side of the rail and a plane supporting surface on the opposite side, coupling elements projecting from the opposite longitudinal ends of the rail adapted to be engaged with a second rail when the latter is in an angular position and interlockingly joined when the sections are in linear position, the said rail hav- 120 125 130

ing the opposite longitudinal ends thereof angularly cut to admit of limited inward flexing of said rails.

8. A railway track rail shaped to double channel form longitudinally to provide an approximately plane wheel tread surface and a wheel flange channel on one side and a plane supporting surface on the opposite side, flexible coupling elements at each of the ends of said rail for detachably connecting the latter with adjoining rails, the said rail having the opposite longitudinal ends thereof angularly shaped to produce a V-

shaped gap between adjacent rail ends whereby said rail is automatically brought ¹⁵ into track gage by the passage of rolling stock thereover.

9. In a track-way, co-operating track sections, each comprising a tread portion and supporting means at the opposite edges of ²⁰ the tread portions, and means for movably connecting the sections at one of said supporting edge portions.

In testimony whereof I affix my signature.

NORTON A. NEWDICK.
